NATHANIEL BOIS, OF SAN FRANCISCO, CALIFORNIA.

INTERLOCKING STAIR-FORM.

1,244,021.

Specification of Letters Patent. Patented Oct. 23, 1917.

Application filed August 27, 1914. Serial No. 859,266.

To all whom it may concern:

Be it known that I, NATHANIEL BOIS, a citizen of the United States, residing in the city and county of San Francisco and State of California, have invented a new and useful Improvement in Interlocking Stair-Forms, of which the following is a specification.

My invention relates to interlocking stair forms wherein each unit, comprising a stair, is formed with an offset riser integral with a tread having a nosing, also formed integral therewith and arranged to interlock with the nosing on the tread of the stair 10 above it; and the objects of my invention are first, to provide an improved stair form arranged to interlock with the stair forms adjoining it; second, to provide a nosing of a double thickness for each tread for 15 strengthening purposes; third, to provide a nosing arranged to rigidly engage the top of the riser of the stair below it; fourth, to provide a stair form having a pocket in the tread and lower portion of the riser for the 20 reception of concrete; fifth, to provide a concrete tread that shall extend into the riser so as to form a round sanitary corner and also form a wearing surface for a portion of the said riser, and sixth, to eliminate 25 the necessity for bolts, rods, nuts and the like.

I accomplish these several features by means of the device disclosed in the drawings forming a part of the present specification wherein like characters of reference 35 are used to designate similar parts throughout the said specification and drawings, and in which—

Figure 1 is a perspective view, partly in 40 section, disclosing the general form and arrangement of the stair forms secured together.

Fig. 2 is an enlarged broken sectional view of one of the stair forms and a portion 45 of each adjacent form, disclosing the pocket for the concrete tread and the manner in which the nosing of the stair above interlocks with the nosing on the riser of the stair below it.

Fig. 3 is a detailed view of the nosings 50 being interlocked.

Fig. 4 is a partial front elevation of a portion of a stairway built of my forms.

Fig. 5 is a sectional view of a modified

form of stair form wherein the nosings are 55 formed semicircular, and

Fig. 6 is a detailed view of the semicircular nosings disclosing the manner in which one semicircular nosing is inserted and interlocked within the other.

The numeral 1 is used to designate the stringers to which are fastened the angle irons 2 for the support of the stair forms. The stair forms comprise a tread 3 having an upturned channel 4 on the front edges 65 thereof, so as to form a suitable nosing. The risers 5 are formed integral with the tread 3 and have the upper portions thereof slightly offset toward the front of the tread 3, the lower portion 6 of the said offset portion being slightly above the top of the nosing 4 formed in the front edge of the tread 3. In this manner a pocket is formed for the reception of concrete, which pocket will give a concrete tread 7 having a lateral extension 8 at the rear end thereof, said extension 8 forming the lower portion of the riser, which construction will also permit of a sanitary curved corner 9 to be formed therein. The curved sanitary corner 9 will 70 also produce a greater strength between the concrete tread 7 and the extension 8 thereto and thereby strengthen the junction of the said tread 7 and the extension 8 thereof.

The top of the riser 5 has formed thereon 85 a channel 10 having the back thereof turned toward the front of the tread 3.

A depending flange 12 on the back portion of the said channel 10 at the top of the riser 5, forms a nosing in conjunction with the 90 said channel 10, which is arranged to surround and engage the nosing 4 of the tread 3 on a similar stair form above it. Similarly, the nosing 4 on the front edge of the tread 3 is engaged by the channel 10 and depending flange 12 formed on the riser 5 on the stair form below it. In this manner the 95 stair forms are interlocked and rigidly secured to each other, so that after the concrete is set in the pocket of the tread it will 100 be impossible to disengage one stair form from another without destroying the stair form.

A further advantage is that the nosing is 105 formed of a double thickness of material which will thereby impart greater strength to the front of each tread, which is subjected to the greatest amount of wear.

The lower portion of the riser 5 being off-set so as to accommodate its surface to the front surface of the concrete extension 8, it can be readily seen that the lower portion 5 of the said tread 5 which is exposed to the greatest wear will be composed of a heavier and more durable material, thereby extending the life of each riser.

In Figs. 5 and 6, I have illustrated a modified form wherein the nosings are formed of semicircular channels for purposes of appearances. In this form there will be no sharp edge of the nosing exposed to wear and the depending flange 14 on the edge of the semicircular channel 10' will engage the semicircular nosing 4' of the tread 3 in the manner heretofore described for the preferred form of the invention.

In Fig. 6 I have illustrated the manner in which the curved nosing 4' of the tread 3 may be inserted into the curved channel 10' of the riser 5.

It is obvious from the foregoing that I have provided an improved stair form wherein each unit is formed with an offset riser integral with the tread and having a nosing also formed integral therewith and arranged to interlock with the nosing on the tread of a similar stair above it.

Having thus described my invention what I claim as new and desire to secure by Letters Patent is—

The combination with a stair form having a tread, a riser connected thereto, and a rearwardly facing channel formed on the upper edge, said channel comprising a bottom wall, a top wall and a forward side wall, and a depending flange formed on the rear edge of the top wall, of a second stair form having a tread, and a nosing formed on the forward edge thereof, said nosing comprising an upstanding wall and rearwardly extending wall on the upper edge of the last mentioned wall, the forward portion of the tread projecting into said channel in contact with the bottom wall thereof and the nosing fitting within the channel in continuous contact with the side wall and top wall thereof, the depending flange extending below the plane of the top wall of the nosing. 35 40 45 50

In witness whereof I hereunto set my signature in the presence of two subscribing witnesses.

NATHANIEL BOTS
